CLOSED ENTRY SOCKET

Henry P. Dupre, Wilton, Conn., assignor to Burndy Corporation, a corporation of New York

Filed Oct. 28, 1958, Ser. No. 770,133

5 Claims. (Cl. 339—217)

This invention relates to electrical connectors of the mating pin and socket type and, more particularly, to a socket contact having means to transform the end to a closed entry.

One common form of electrical connector includes a male or pin element coupled to one conductor of the circuit and a mating socket contact coupled to the other conductor to be joined. By engaging the pin and socket contacts, the electrical circuit is completed. In the past it has been found desirable to include means in the socket contact which would apply a pressure to the contained pin contact to ensure proper electrical connection and to increase the pressure necessary to withdraw the pin contact from the socket. One common form of socket contact including such spring pressure means comprised a socket having a plurality of spring-like fingers surrounding the pin element. For ease of manufacture the tubular barrel of the socket contact was slit to form the spring-like fingers.

In use, such a socket contact had many disadvantages. The foremost among these disadvantages was the fact that this type of contact was not a "closed entry." In other words, because the spring fingers extended along the total length of the contact end, the barrel of the socket could be overexpanded to accept an oversized pin, and thus the socket contact would be damaged through the use of an improper mating portion.

In order to overcome this disadvantage of opened contacts, unitary contacts have been designed in which the end first accepting the pin was closed and various other methods of providing the necessary spring pressures were utilized. Some of these methods included the use of additional spring elements or a different form of slitting the tubular barrel of the socket contact to provide spring fingers along a length of barrel, not including the entrance. While these sockets have performed satisfactorily, they have been found expensive to produce and difficult to use.

One of the objects of my invention, therefore, is to provide a novel closed entry socket.

Another object of my invention is to provide a novel closed entry contact having spring finger elements along substantially the entire length of the tubular barrel.

A further object of my invention is to provide a closed entry socket adapter to transform an easily manufactured spring fingered socket contact to a closed entry type of socket contact.

Still another object of my invention is to provide a closed entry socket contact structure which may be easily removed from its associated insulating panel.

One of the features of my invention is the provision of a socket contact having substantially its entire barrel slit to form spring finger contact elements to apply pressure to a mating pin contact. Upstanding from the tubular body portion of the socket contact is a plurality of locking elements which cooperate with shoulders in the insulating panel to lock the socket within the panel and which may be easily depressed so that the socket may

2

be removed from the panel. A closed entry adapter is utilized to restrict the entrance of oversized pin contacts and has openings therein through which the locking ears of the socket contact fingers extend so that the closed entry adapter does not interfere with the locking function.

These and other features and objects of the invention will become more apparent by reference to the following description taken in conjunction with the accompanying drawings in which:

Fig. 1 is an exploded side view partly in section of the socket contact and closed entry adapter of my invention;

Fig. 2 is a side view partly in section of the closed entry adapter mounted on the socket contact assembly in accordance with my invention;

Fig. 3 is an end view in cross section taken along the lines 3—3 of Fig. 2;

Fig. 4 is a side view partly in cross section of the cooperating pin and socket contacts of my invention mounted in a supporting insulating housing; and

Fig. 5 is a perspective view of an alternate embodiment of the closed entry adapter of my invention.

Referring to Fig. 1 of the drawing, an exploded view 15 of the socket contact assembly in accordance with the principles of my invention is therein seen to comprise a socket contact 10 and closed entry adapter 12. The socket contact 10 includes a wire receiving barrel 14 in which the bared wire to be joined is inserted and an insulation grip 15. Forward of the wire barrel 14 is the tubular connector receiving portion 16 and a tubular connector receiving portion 17 of greater diameter. The tubular portions 16 and 17 have slits 18 there along forming a plurality of spring-like fingers on the barrel portion. The spring-like fingers surround the tubular portion which accepts the mating pin contact. Upstanding from the spring-like fingers are locking elements 22.

The closed entry adapter comprises a mounting portion 24 and a closed entry portion 28 having openings 26 therebetween. As shown in Fig. 2, the mounting portion fits over the spring-like fingers of the socket contact 10. Opposite sides of the spring-like contacts may first be sawed to provide easy mounting for the closed entry adapters. The locking elements 22 of the adapter extend through the opening 26 as hereinafter explained.

In use, as shown in Fig. 4, an electrical conductor 13 has its insulation 19 stripped back and inserted in the barrel 14 which is crimped thereto. The insulation grip 15 of the socket contact 10 is crimped about the insulation 19 in the usual manner. The socket contact 10 and closed entry adapter 12 are inserted in the barrel of the housing 44, and during the insertion, the spring locking members 22 are depressed to pass through the restricted portion. After passing through the restricted portion, the locking fingers 22 engage the shoulder 40 to prevent withdrawal of the socket contact and the shoulders 42 of the housing engage shoulders of tubular portion 17 to prevent overinsertion of the socket contact. In a similar manner a pin contact 30, having locking spring element 36, is inserted in housing 32 and locked therein between shoulders 38 and 39. In use, the pin contact 30 is inserted past the closed entry of the adapter 12 into the tubular portion 16 of the socket contact 10. The spring fingers tightly engage the pin contact making electrical and mechanical connection thereto positive. The closed entry adapter 12 prevents the insertion of an oversized pin member.

Referring to Fig. 5 of the drawing, an alternate embodiment of the closed entry adapter of my invention is therein shown to utilize a slit 46 in the mounting member. Thus the slit 46 may be opened, and the closed entry adapter may be mounted over the spring-like fingers

of the socket contact, avoiding any overcompression or stressing of the spring-like fingers due to their insertion within the closed entry. Once properly positioned over the socket contact, the upper and lower elements of the closed entry adapter may be closed about the barrel.

It is, of course, obvious that the socket contact of my invention need not have four fingers, but may be made with two or any other number of fingers. Preferably, the round sides of the socket contact should be flattened on opposite sides to permit the closed entry adapter to be disposed over the socket contact. To remove the contact from the panel, a tubular tool is positioned over the locking elements 22, depressing the same and permitting withdrawal of the connector from the panel.

I have thus described my invention, but I desire it understood that it is not confined to the particular forms or uses shown and described, the same being merely illustrative, and that the invention may be carried out in other ways without departing from the spirit of my invention, and therefore, I claim broadly the right to employ all equivalent instrumentalities coming within the scope of the appended claims, and by means of which, objects of my invention are attained and new results accomplished, as it is obvious that the particular embodiments herein shown and described are only some of the many that can be employed to attain these objects and accomplish these results.

I claim:

1. An electrical contact assembly comprising a metallic contact body including a conductor attaching portion and a body portion, said body portion including a plurality of resilient fingers having radially projecting means thereon, said fingers adapted to receive a mating contact therebetween; a closed entry adapter mounted on said contact body, said adapter including an end having an unbroken periphery and adapted to receive the mating contact, a mounting end adapted to receive said fingers, and a plurality of openings therebetween; said spring fingers' radially projecting means extending through said openings.

5. An electrical contact assembly comprising a contact body having a conductor attaching portion and a tubular mating contact receiving portion, said tubular portion including a plurality of resilient fingers having radially projecting means thereon, a closed entry adapter including a cylindrical contact receiving portion having an unbroken periphery and means to mount said adapter on said contact body, and means joining said cylindrical portion and mounting means whereby a plurality of openings are formed therebetween for extending the radially projecting means of said resilient fingers therethrough.

2. An electrical contact assembly according to claim 1 wherein said adapter mounting means includes a cylindrical portion having at least two longitudinal slits therein.

3. A contact assembly according to claim 2 wherein

10 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

4. A contact assembly according to claim 2 wherein said tubular portion includes a length having an outside diameter less than the outside diameter of the remainder of the tubular portion and said adapter is mounted on the tubular portion of less outside diameter.

5. An electrical contact assembly comprising an insulating housing having a bore therethrough, said bore including a restricted portion forming a front locking shoulder and a rear locking shoulder, a tubular contact body having a conductor attaching portion and a tubular

20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

contact receiving portion, said tubular portion including a plurality of resilient fingers having radially projecting means thereon, and at least a portion of said contact body including a section of greater outside diameter to form a rear locking shoulder, a closed entry adapter including a cylindrical contact receiving portion, means to mount said adapter on said body and a plurality of openings in said adapter and the radially projecting means of said resilient fingers at least in part disposed therethrough to cooperate with the front locking shoulder of said insulating housing.
